UNITED STATES PATENT OFFICE.

GEORGE GILLARD GORDON, OF DOLLIS HILL, LONDON, ENGLAND.

DISINFECTANT COMPOSITION.

No Drawing. Application filed December 17, 1926, Serial No. 155,543, and in Great Britain June 29, 1925.

This invention comprises a novel or improved process for the production of a liquid disinfectant composition and the product of such process, involving the use as ingredients of a eucalyptus oil or extract and a saponaceous vehicle for the eucalyptus content.

Broadly stated, the process consists in mixing one or more oils or extracts of the 10 eucalyptus species with an oleaginous ingredient until solution of the latter and adding an aqueous alkaline solution which, together with the oleaginous ingredient, forms a saponaceous vehicle for the eucalyptus content, until the latter reaches or approximates 37% of the whole.

The invention also comprises other steps of the process, the provision of substitutes for certain of the ingredients and the product of the process, all as hereinafter set forth and defined in the appended claims.

Taking as an example a process for producing 10 gallons of the liquid disinfectant, I proceed as follows, using the ingredients 25 specified, or certain substitutes hereinafter mentioned, in substantially the proportions stated, although these latter may be somewhat varied according to requirements.

I take 37 lbs. of oil of *Eucalyptus phellandria* or oil of *Eucalyptus Australiana* and add thereto 2 lbs. of oil of *Eucalyptus citriodora*, these ingredients being mixed with 2 lbs. of ground rosin or equivalent such as oleic acid or other suitable oil such as cotton seed oil or linseed oil and allowed to remain until the rosin is dissolved, a period of twenty-four hours being usually sufficient for this purpose with the mixture stirred from time to time. To the said mixture are 35 then added 2 gallons of an aqueous solution of an alkali such as caustic soda, for instance a 2½% solution of 98% purity. The composition is thoroughly mixed, say for a period of four hours, additional water being added containing for example 1½% caustic soda until the eucalyptus content reaches or approximates 37% of the whole.

The rosin or other substitutional ingredient used and the alkali together produce 50 a saponaceous mixture which constitutes a vehicle for the eucalyptus content in which the latter remains substantially or completely fixed.

The mixture is again allowed to stand 55 for a period of say two hours, after which it may be tested against maximum and

minimum temperatures against separation of the oils, such separation, if any should occur, being rectified by the addition of a material to correct the balance of water content, such as rosin soap or other saponifying substance.

In producing the disinfectant it is desirable that the oils selected should be those having the highest bacteriological values 60 and care is taken that the whole of the products of distillation from the leaf is obtained, but any oil of the eucalyptus species can be used, the result of the carbolic acid efficiency varying according to the species 65 selected.

As eucalyptus extracts previously referred to there may be mentioned cineol, phellandrene and piperitone which are suitable 70 for the process.

As a substitute for the two special eucalyptus species previously referred to there may be mentioned *E. elaeophora* and *E. sideroxylon*, usually mixed together and marketed by distillers in mixed condition. 80 Again the 2 lbs. of *Eucalyptus citriodora* previously mentioned may be replaced by oil of lemon grass to obtain the odour desired.

It should be remarked it is an established fact that from a 37% mixture of eucalyptus oil with rosin soap or other saponifying matter, the greatest bacteriological value of eucalyptus oil is obtained, superior even to mixtures having a higher percentage of such oil. Hence the special insistence of such percentage or approximate percentage of oil in the present process.

What I claim as my invention and desire to secure by Letters Patent of the United States is:—

1. A process for the production of a disinfectant composition consisting in mixing an oleaginous substance of the eucalyptus species with an oleaginous ingredient until solution of the latter, and adding an aqueous alkaline solution, which, together with said oleaginous ingredient, forms a saponaceous vehicle for the eucalyptus content, until the latter approximates 37% of the whole.

2. A process for the production of a disinfectant composition consisting in mixing an oil of the eucalyptus species with an oleaginous ingredient until solution of the latter, and adding an aqueous alkaline solution, which, together with said oleaginous

ingredient, forms a saponaceous vehicle for the eucalyptus content.

3. A process for the production of a disinfectant composition consisting in mixing an oleaginous substance of the eucalyptus species with ground rosin, and allowing to stand until the rosin is dissolved, and adding an aqueous solution of caustic soda, the latter and the ground rosin forming a saponaceous vehicle for the eucalyptus content, until the latter approximates 37% of the whole.

4. A process for the production of a disinfectant composition, consisting in mixing oil of *Eucalyptus phellandra* with oil of *Eucalyptus citriodora* and with an oleaginous ingredient until solution of the latter, and adding an aqueous alkaline solution which, together with said oleaginous ingredient, forms a saponaceous vehicle for the eucalyptus oils, until the proportion of the latter approximates 37% of the whole.

5. A process for the production of a disinfectant composition, consisting in mixing oil of *Eucalyptus phellandra* and oil of *Eucalyptus citriodora* with ground rosin and oleic acid until solution of the rosin, and then adding an aqueous solution of caustic soda until the eucalyptus oils approximate 37% of the whole.

6. A process for the production of a disinfectant composition, consisting in mixing an oleaginous substance of the eucalyptus species with an oleaginous ingredient until

solution of the latter, adding an aqueous alkaline solution which, together with said oleaginous ingredient, forms a saponaceous vehicle for the eucalyptus content, and testing the mixture against separation of the eucalyptus content.

7. A process for the production of a disinfectant composition, consisting in mixing an oleaginous substance of the eucalyptus species with an oleaginous ingredient until solution of the latter, adding an aqueous alkaline solution which, together with said oleaginous ingredient, forms a saponaceous vehicle for the eucalyptus content, until the latter approximates 37% of the whole, and testing the mixture against separation of the eucalyptus content, such separation if occurring being rectified by addition of a substance adapted to correct the balance of water contents.

8. A disinfectant composition comprising an oil of the eucalyptus species and a saponaceous vehicle for the eucalyptus including alkali and water, with the eucalyptus content approximating 37% of the whole.

9. A disinfectant composition comprising an oil of the eucalyptus species, ground rosin dissolved in said eucalyptus, caustic soda and water, with the eucalyptus content approximating 37% of the whole.

In witness whereof I have signed this 65 specification.

GEORGE GILLARD GORDON.
